UNITED STATES PATENT OFFICE.

LYCURGUS B. RILEY, OF GRAFTON, ILLINOIS.

GRAIN-MEASURE.

SPECIFICATION forming part of Letters Patent No. 434,467, dated August 19, 1890.

Application filed April 21, 1890. Serial No. 348,926. (No model.)

To all whom it may concern:

Be it known that I, LYCURGUS B. RILEY, of Grafton, in the county of Jersey and State of Illinois, have invented a new and Improved 5 Grain-Measurer; and I do hereby declare that the following is a full and exact description of the same, reference being had to the accompanying drawings, and to the letters of reference marked thereon.

10 My invention relates to an improvement in grain-measurers, my object being to provide a measurer more convenient and more easily operated than those of its class heretofore in use. These ends I accomplish by a peculiar 15 construction and combination of parts, fully explained in the following specification, and illustrated in the accompanying drawings, in which—

Figure 1 is a side elevational view of the 20 measurer, partly shown in section, taken in the line *xx* in Fig. 2, which is a plan or top view of the machine; and Fig. 3 is a front end elevation thereof, taken in the line *yy*, Fig. 2.

Referring to the drawings, A represents the 25 frame of the machine supporting a table B, provided with a wide slot E, adapted to receive (so that it will slide freely therein) the lower end of an externally-cylindrical measuring-vessel *i*, the latter having a shoulder S, (see Fig. 3,) formed so as to rest upon the table B. The interior of said measuring-vessel is 30 preferably conical or funnel-shaped, and has its upper end secured in the forward part of the bottom of an oblong horizontally-sliding 35 box C, the rear part of which is supported upon a shelf D, (shown in Fig. 1,) the ends of which are secured to the frame A.

Pivotedly secured at *r* are two forward-projecting arms, from the forward extremities of 40 which depends vertically, so as to reach across the interior of the box C and rest upon the bottom thereof, a scraper *g*.

Immovably secured between the top horizontal bars of the frame A is a partition *h*, projecting downward almost to the bottom of the 45 box C and of such width as to reach from side to side of the interior, with only sufficient play between it and the box to allow the latter to slide freely in a horizontal direction.

50 To the bottom of the measuring-vessel *i* is suspended upon cross-bars *ll*, as shown in

Figs. 1 and 3, a horizontally-sliding door *k*, having an opening *o* of the same size and form as the outlet in the bottom of the measuring-vessel *i*.

55

To the under side of the table B, in a position transverse to its length, are secured two cross-bars F F'.

To the front side of the measuring-vessel, as shown at J, Fig. 1, is a handle by which the 60 machine is operated.

The spout, purposely omitted in the drawings, by which the grain is conducted to the machine being adjusted over the measuring-vessel when the latter is in the position shown 65 in Fig. 1, the sack to be filled is sustained by hooks or other suitable means beneath the table B in proper position to receive the grain when discharged from the vessel *i*. Matters being thus, the grain is allowed to flow into 70 the measure, and when the latter is filled, so as to overflow its upper edges, the flow of grain from the supply-spout is stopped or not, as may be desired, and the operator standing in front of the machine and taking hold of 75 the handle J draws the measuring-vessel toward him in the direction indicated by arrow 1 until it reaches the forward extremity of the slot E, and, as will be noticed, with it the box C. Now as the measuring-vessel approaches the forward extremity of its travel 80 the front end of the sliding door *k* comes in contact with the forward cross-bar F, as indicated by arrow 2, and by the completion of the measurer's travel the sliding door is thrust 85 backward with reference to the measuring-vessel to such a position that the opening *o* is coincident with the orifice in the bottom of the vessel *i* and the latter's contents instantly fall into the sack provided for its reception. 90

It will be observed that as the measure is drawn forward for the purpose of being discharged the scraper *g* being immovable horizontally and its lower edge resting on the upper edge of the measure, it will remove all the 95 grain that is heaped above the top edge thereof. It will be further observed that the end of the door *k* does not come in contact with the cross-bar F until the measure has been drawn sufficiently far forward for the 100 scraper to have passed completely over the top of it, making the contents of the measure

flush with the top thereof, the superfluous grain being retained between the scraper and the partition *h* and resting upon that part of the bottom of the box *C* which, when the 5 measure is drawn forward into position for being discharged, occupies the place of the top of the measure when the latter is in position for being filled, as shown in Fig. 1.

In regard to the means employed for closing the door *k* after the contents of the measure have been discharged, it will be observed that the end of the door as the measure is pushed back comes in contact with the cross-bar *F'* and closes the orifice in the bottom of 10 the measure, and the grain scraped from the top of the measure onto the bottom of the box *C* is as the latter moves backward pushed by the partition *h* into the vessel *i*, which is again filled by the supply-spout.

15 Having fully described my invention, what I claim as new, and desire to secure by Letters Patent, is—

In a grain-measurer, a horizontally-sliding box *C*, having a funnel-shaped measuring-vessel *i* secured in the bottom thereof, a 25 slotted supporting-table *B*, a supporting-shelf *D*, a scraper *g*, pivotally secured to an immovable part of the frame *A*, a partition *h*, secured also to an immovable part of the frame *A*, a sliding door *k*, and cross-bars *F* 30 and *F'*, and a handle *J*, secured to the measuring-vessel, all of said parts constructed, combined, and adapted to each other for united operation, substantially as and for the purpose herein set forth.

35 In testimony that I claim the foregoing I have hereunto set my hand this 20th day of January, A. D. 1890.

LYCURGUS B. RILEY.
